UNITED STATES PATENT OFFICE.

EARL A. SHANKWEILER, OF ALLENTOWN, PENNSYLVANIA.

DESIGN FOR A LOUD-SPEAKER LAMP.

Application filed January 11, 1926. Serial No. 16,025. Term of patent 3½ years.

To all whom it may concern:

Be it known that I, EARL A. SHANKWEILER, a citizen of the United States, residing at Allentown, in the county of Lehigh and State of Pennsylvania, have invented a new, original, and ornamental Design for a Loud-Speaker Lamp, of which the following is a specification, reference being had to the accompanying drawing, forming part thereof.

Figure 1 is a front elevation of a loud speaker lamp showing my new design.

Figure 2 is a top plan view thereof.

Figure 3 is a section on line 3—3 Figure 1.
I claim:

The ornamental design for a loud speaker lamp, as shown.

EARL A. SHANKWEILER.
